BOBBIN WINDER

Waldemar A. Ayres, Lakewood, Ohio, assignor to White Sewing Machine Corporation, Lakewood, Ohio, a corporation of Delaware

Application May 12, 1954, Serial No. 429,317

10 Claims. (Cl. 242—22)

This invention relates to bobbin winders for sewing machines, and more particularly to a type of bobbin winder which automatically stops itself when fully wound such that the continued attention of an operator is not required once the bobbin winding operation is started.

One of the objects of this invention is to provide an improved bobbin winder of the class described which will be of the simplest design and which will contain a minimum of parts.

It is a further object of the invention to provide a small and compact unit which will not extend appreciably beyond its supporting structure, such as the head of a sewing machine, and which will not contain projecting portions which interfere with the movements of an operator.

It is a more particular object of this invention to provide a device of the class described which utilizes a frictional drive connection between the bobbin and its driving spindle or shaft, and which also uses frictional braking means to engage the wound material on the bobbin when it reaches a predetermined diameter and whose braking torque will exceed that of the frictional drive connection and so stop the winding rotation of the bobbin.

It is a still further object of this invention to utilize two frictional braking elements to engage portions of the bobbin which are substantially 180 degrees apart, such that the thrust exerted by the revolving bobbin on one element will be substantially equal and opposite to that exerted on the other element and such that the structure containing the elements will not be forced out of engagement with the revolving bobbin.

Other objects and advantages will be apparent during the course of the following description.

In the accompanying drawing forming a part of this specification like numerals are employed to designate like parts throughout, and wherein:

Fig. 1 is a side elevational view of a preferred embodiment of the present invention;

Fig. 2 is a sectional view taken along the lines 2—2 as shown in Fig. 1, and

Fig. 3 is a fragmentary enlarged exploded view showing partly in section and partly in elevation the engaging portion of the driving shaft and the friction driving connection carried thereby and a bobbin ready to be inserted upon said portion of the shaft to be driven thereby.

In the drawing, wherein for the purpose of illustration is shown a preferred embodiment of the invention, the numeral 10 designates a spindle rotatably supported in a housing 11 and having a cantilevered end portion for receiving a bobbin 12. The housing 11 may be a sewing machine head and the spindle or shaft 10 may be continuously rotated by the mechanism of the machine in any well known manner. The bobbin comprises a hub portion 13 having a smooth interior cylindrical surface 14 having flanges 15 at either end for confining thread and the like wound upon the bobbin.

The invention forming the subject matter of this appli-

2

cation consists in part of frictional driving means comprising a pivoted arm or detent 16 positioned within a groove or slot 17 milled into the cantilevered portion of the spindle. The side surfaces of the detent fit snugly against the sides of the milled groove so as to prevent wobbling of the detent in the groove, and the detent is held in place as by a pivot pin 18 inserted through the shaft and through one end of the detent. The detent is forced outwardly as by means of a spring 20 positioned between the bottom of the groove and the bottom of the detent such that the detent will always engage the inside 14 of the hub of a bobbin installed upon the spindle. This springing action coupled with any centrifugal force of the detent produced by rotation of the spindle forces the detent against the inside of the hub sufficiently to establish a driving frictional engagement between the spindle and the hub. It is to be noted that the bobbin is driven by means of this frictional engagement alone and not by means of a keying action between the spindle and bobbin. As such, this frictional engagement may be accomplished by all types of sizes and shapes of detents, springs and the like, all of which are to be considered the equivalent of the preferred embodiment shown in the drawings.

According to the principles of the present invention, the driving frictional engagement between the spindle and the bobbin is to be opposed by a braking frictional engagement which overcomes the former when a predetermined amount of material is wound upon the bobbin. The embodiment shown in the drawings utilizes a plate 30 having a pair of horizontal fingers or elements 31 and 32 adapted to extend between the flanges 15 of the bobbin and engage the wound material on the bobbin when its diameter substantially equals the vertical spacing of the fingers.

The braking structure can be formed as by removal of a central rectangular portion adjacent one end of a plate so as to leave top and bottom projections whose width corresponds to that of the desired friction elements. The upper and lower edges of the plate containing these projections can then be bent perpendicularly to the main body of the plate to establish the desired horizontal relationship of the elements. The frictional structure thus formed can be slidingly attached to the sewing machine or like housing for movement into and out of its braking position by means of bolts 33 extending through a slot 34 formed along the longitudinal centerline of the plate 30. A suitable projection 35 on the housing positions the braking structure relative to the bobbin and an enlarged shank portion 36 on each bolt slidably engages the edges 37 of the slot to firmly guide the friction elements into and out of their braking position between the flanges of the bobbin. To facilitate moving this structure, a handle 38 is provided as by bending the left-hand edge of the plate into a substantially perpendicular position.

Operation of the device consists of inserting the bobbin 12 onto the spindle 10, tying the material to be wound onto the bobbin, sliding the braking structure into engagement with the bobbin and starting rotation of the spindle. The operator of the machine to which this device is coupled need not further concern himself with the winding operation until such time as he desires to remove the bobbin. As the material becomes wound upon the bobbin, its diameter steadily increases until such time as it engages the braking elements 31 and 32. During the initial contact of the material with the elements sufficient force is not produced to counteract that of the frictional driving means. By continued rotation of the bobbin, however, additional material is wound upon the bobbin forcing the elements 31 and 32 to bend outwardly until sufficient frictional force is produced

between the friction elements and the material to exceed that of the driving engagement. At this time, the bobbin 12 stops rotating and the shaft 10 with its detent continues to revolve inside of the hub of the bobbin until the operator notices that the bobbin is fully wound and removes the same from its spindle.

It will be noted that the braking structure of the preferred embodiment utilizes a pair of friction elements spaced to engage portions of the wound material that are substantially 180 degrees apart. With reference to Fig. 1 of the drawings, it will be seen that clockwise rotation of the bobbin produces a force on the top element 31 tending to drag it further into engagement, and that it produces a force on the bottom element 32 tending to force it out of engagement. Since the friction elements are equally spaced on opposite sides of the centerline of the spindle, these forces are substantially equal and so counteract each other with the result that the braking structure 30 does not move relative to the revolving bobbin.

Other modifications will suggest themselves to those skilled in the art. One such modification would be to provide frictional driving surfaces between the side of a flange mounted on the spindle and the side of a bobbin yieldably retained upon the spindle. A split shaft whose portions are bent outwardly to receive the bobbin might also suggest itself to those having the benefit of the above disclosure. All such modifications fall within the contemplation of the present invention and are to be regarded as equivalents.

Although the bobbin winding device of the present invention has been illustrated and described herein to a detailed extent, it will be understood, of course, that the invention is not to be regarded as being limited correspondingly in scope, but includes all changes and modifications coming within the terms of the claims hereof.

Having thus described my invention, I claim:

1. A bobbin winder for a sewing machine structure comprising, a spindle mounted by said structure and adapted to be rotated by the sewing machine mechanism and to support a bobbin; means for establishing frictional driving engagement between said spindle and a bobbin mounted thereon; and means supported by said structure establishing braking frictional engagement with the material wound upon said bobbin whereby sufficient braking torque is developed to offset and exceed the driving torque and thereby stop the bobbin's rotation.

2. A bobbin winder for a sewing machine structure comprising, a spindle mounted by said structure and adapted to be rotated by the sewing machine mechanism and to support a bobbin; means for establishing frictional driving engagement between said spindle and a bobbin mounted thereon; and braking frictional engagement means mounted on said structure and positioned between the flanges of the bobbin to bear against and frictionally engage coiled portions of material wound on the bobbin whereby sufficient braking friction is developed to substantially equal and offset the driving friction between the frictional driving means and the bobbin and thus stop the bobbin's rotation.

3. A bobbin winder for a sewing machine structure comprising, a spindle mounted by said structure and adapted to be rotated by the sewing machine mechanism and to support a bobbin; means for establishing frictional driving engagement between said spindle and a bobbin mounted thereon; and a flat blade-like projection suitably held by said structure for positioning between the flanges of said bobbin whereby sufficient braking torque is developed between material wound on said bobbin and said blade-like projection to offset the driving torque produced by said first means and thereby stop rotation of the bobbin.

4. A bobbin winder for a sewing machine structure comprising, a spindle mounted by said structure and adapted to be rotated by the sewing machine mechanism

and to support a bobbin; means for establishing frictional driving engagement between said spindle and a bobbin mounted thereon; and a plurality of flat blade-like projections suitably held by said structure for positioning between the flanges of said bobbin whereby sufficient braking torque is developed between material wound on said bobbin and said blade-like projections to offset the driving torque produced by said first means and thereby stop rotation of the bobbin.

5. A bobbin winder for a sewing machine structure comprising, a spindle mounted by said structure and adapted to be rotated by the sewing machine mechanism and to support a bobbin; means for establishing frictional driving engagement between said spindle and a bobbin mounted thereon; and a braking structure suitably mounted on said structure and having a pair of flat blade-like projections substantially parallel to each other for positioning between the flanges of said bobbin and engaging portions of the wound material on the bobbin which are substantially 180 degrees apart from each other, whereby the torque produced by the frictional engagement between the material wound on the bobbin and its frictional engagement means substantially overcomes that between the bobbin and the first-mentioned means to stop rotation of the bobbin when the material wound on the bobbin reaches a predetermined diameter.

6. A bobbin winder for a sewing machine structure comprising, a spindle mounted by said structure and adapted to be rotated by the sewing machine mechanism and to support a bobbin; a detent suitably affixed to said spindle for engagement with the inside cylindrical surface of a bobbin installed on said spindle; means for maintaining engagement between said detent and said bobbin; and a pair of flat blade-like projections suitably held by said structure for positioning between the flanges of the bobbin, whereby the torque produced by the frictional engagement between the material wound on the bobbin and its frictional engagement means substantially overcomes that between the bobbin and its detent to stop rotation of the bobbin when the material wound on the bobbin reaches a predetermined diameter.

7. A bobbin winder for a sewing machine structure comprising, a spindle mounted by said structure and adapted to be rotated by the sewing machine mechanism and to support a bobbin; a detent suitably affixed to said spindle for engagement with the inside cylindrical surface of a bobbin installed on said spindle; means for maintaining engagement between said detent and said bobbin; and a braking structure suitably mounted on said structure and having a pair of flat blade-like projections substantially parallel to each other for positioning between the flanges of said bobbin and engaging portions of the wound material on the bobbin which are substantially 180 degrees apart from each other, whereby the torque produced by the frictional engagement between the material wound on the bobbin and its frictional engagement means substantially overcomes that between the bobbin and its detent to stop rotation of the bobbin when the material wound on the bobbin reaches a predetermined diameter.

8. A bobbin winder for a sewing machine structure comprising, a spindle mounted by said structure and adapted to be rotated by the sewing machine mechanism and to support a bobbin; a detent suitably affixed to said spindle for engagement with the inside cylindrical surface of a bobbin installed on said spindle; spring means for yieldably urging said detent against said bobbin; and a braking structure suitably mounted on said structure and having a pair of flat blade-like projections substantially parallel to each other for positioning between the flanges of said bobbin and engaging portions of the wound material on the bobbin which are substantially 180 degrees apart from each other, whereby the torque produced by the frictional engagement between the material wound on the bobbin and its frictional en-

gagement means substantially overcomes that between the bobbin and its detent to stop rotation of the bobbin when the material wound on the bobbin reaches a pre-determined diameter.

9. A bobbin winder for a sewing machine structure comprising, a spindle rotatably supported by said structure and having a portion projecting externally of said structure; a longitudinal groove in the projecting portion of said spindle; a detent mounted in said groove and adapted to yieldably bear against the inside cylindrical surface of a bobbin mounted on said shaft; a plate-like member having projections adapted to be inserted between the flanges of a bobbin mounted on said shaft, said plate-like member being slidably mounted on said structure in a manner so as to be capable of being moved from an inoperative position in which said projections are free of the bobbin to an operative position where the projections are between the flanges of the bobbin; and frictional means for holding said plate-like member in either of its two positions.

10. A bobbin winder for a sewing machine structure comprising, a spindle rotatably supported by said structure and having a portion projecting externally of said structure; a longitudinal groove in the projecting portion of said spindle; a detent pivotally mounted in said groove;

5
10
15

a spring mounted between said detent and the bottom of said groove and adapted to force said detent against the inside cylindrical surface of a bobbin mounted on said shaft; a plate-like member having a pair of substantially parallel projections adapted to be slid into an operative position between the flanges of a bobbin mounted on said shaft; a longitudinal slot in said plate-like member substantially parallel to said projections; and a pair of fasteners in said slot attaching said plate-like member to said sewing machine structure in a manner permitting the member to be slid between said operative position and an inoperative position wherein said projections are free from engagement with said bobbin, said fasteners frictionally retaining said member in either of its two positions.
